(57) **CLAIM**

The ornamental design for a storage box, as shown and described.

DESCRIPTION

FIG. 1 is a front perspective view of a first embodiment of the storage box of my new design;

FIG. 2 is a bottom front perspective view thereof,

FIG. 3 is a top plan view thereof,

FIG. 4 is a front elevation view thereof,

FIG. 5 is a right side elevation view thereof, the left side elevation view is a mirror image of FIG. 5,

FIG. 6 is a rear elevation view thereof,

FIG. 7 is a bottom plan view thereof,

FIG. 8 is a top, front perspective view of a second embodiment of my new design, similar to FIG. 1 except for the stippled portion which indicates a different color or texture from the remaining surfaces; the remaining views of this embodiment are the same except for this difference;

FIG. 9 is a top, front perspective view of a third embodiment of my new design, similar to FIG. 1 except for the omission of the upper crescent shaped recessed area; the remaining views of this embodiment are the same except for this omission; and,

FIG. 10 is a bottom, front perspective view of a fourth embodiment of my new design; the top, right and left side and rear elevation views are the same as FIGS. 3, 5 and 6 except for the inclusion of the casters as seen in FIG. 10. The broken lines shown are for illustrative purposes only and form no part of the claimed design.
